GAS RANGE

John E. Chambers, Shelbyville, Ind.

Application February 10, 1936, Serial No. 63,073

1 Claim. (Cl. 158—115)

My invention relates to gas ranges and especially to gas ranges provided with a pilot-burner arrangement of the explosion type. In that kind of pilot-burner arrangement, a small portion of the gas and air mixture supplied to the main burner is mixed with additional air and conducted through a tube to a pilot-burner which causes a mild explosion within the tube and ignites the main burner.

10 The above described pilot-burner arrangement works satisfactorily as long as the gas issuing from the main burner is unconfined. In some types of gas ranges, however, it is customary to enclose the main burner within a bowl-shaped 15 housing which, when its upper end is covered as with a kettle or other article to be heated, serves to confine the gas issuing from the main burner prior to its ignition with the result that there is sometimes present in the bowl or main-burner 20 housing a considerable volume of explosive gas and air mixture which, when ignited from the pilot burner, is apt to explode with disagreeable consequences.

Broadly stated, it is the object of my invention 25 to prevent or materially decrease the possibility of any undesirable explosion within the main-burner housing when the gas issuing from the main burner is ignited by a pilot-burner arrangement of the explosion type. More specifically, it is my object to prevent the accumulation 30 of a large quantity of gas within the main-burner housing prior to ignition by the pilot-burner. A further object of my invention is to prevent the accumulation of unburned gas in 35 the main-burner housing by means which may be simply and economically embodied in any type of gas range.

A further object of my invention is to produce 40 an improved type of gas burner in which the possibility of interference between flames issuing from different ports is reduced.

In carrying out my invention, I provide for a 45 certain delay of the supply of gas to the main-burner, during which delay an explosive mixture will be conducted to the pilot-burner, with the result that no substantial quantity of gas 50 will have issued from the main-burner by the time the pilot-burner operates. As a practical embodiment of my invention, I provide a passage of considerable extent between the ports 55 of the main burner and the throat through which the mixture of gas and primary air enter, and I supply the tube leading to the pilot burner with a mixture of gas and air from a point closely adjacent to the throat. Preferably, the ports

of the main burner are located near the upper ends of a series of hollow bosses which project upwardly from and are in communication with an annular conduit conveying the mixture of gas and primary air, which annular conduit is partially surrounded by the delaying passage through which it is connected with the burner throat. Conveniently, the annular conduit, the delaying passage, and the throat are all formed in a single metal casting which, immediately inwardly from the throat, is provided with a port through which a portion of the mixture of gas and primary air is supplied to the tube leading to the pilot-burner.

The accompanying drawing illustrates my invention: Fig. 1 is a top plan view of a gas-range burner and an associated pilot-burner arrangement; Fig. 2 is a horizontal section through the lower part of the burner shown in Fig. 1; Fig. 3 is a vertical section on the line 3—3 of Fig. 1 showing the burner and the housing enclosing it in the complete gas range; Fig. 4 is a plan view of the gas burner and its associated housing; Fig. 5 is a diagrammatic plan view of the burner illustrating the arrangement of ports; and Fig. 6 is a vertical section on the line 6—6 of Fig. 1.

The burner proper illustrated in the drawing embodies an annular conduit 10 from which there extend upwardly a plurality of hollow bosses 11 each provided around its top with a circumferential series of gas-ports 12.

In the complete gas-range, the burner described is centrally located beneath a circular opening in the cooking top 15, and from the rim of this opening there depends a generally bowl-shaped enclosure 16 provided in its bottom with a pair of openings 17 through each of which two of the bosses 11 extend. In the open upper end of the housing 16, there is disposed a grid 18 adapted to support a vessel or other object which is to be heated from the burner.

The entire burner is conveniently formed as a single casting of metal, and is provided with a throat 20, a gas-inlet port 21, and a primary-air inlet port 22. A suitable means, such as the disk 23 vertically adjustable by the screw 24, is provided for regulating the effective size of the primary-air inlet port 22. It will be understood that a gas nozzle or "spud" will be located to discharge through the gas port 21 as indicated by the arrow in Fig. 2.

The throat 20 is not directly connected to the annular conduit 10 beneath the bosses 11, but instead is connected thereto through a delaying passage 25 which is conveniently formed in

tegrally with the burner in the casting thereof and which partly surrounds the annular conduit 10, being separated from the conduit 10 by an arcuate partition 26 which, as shown, is approximately 180° extent. Immediately inwardly from the throat 20, the passage 25 is provided with a lateral extension 27 in the upper surface of which is a port 28 through which a small portion of the mixture of gas and primary air passing through the throat 20 is supplied to the tube 29 leading to the pilot burner 30. The arrangement of the port 28, tube 29, and pilot-burner 30 is more fully set forth in the co-pending application of Thomas E. Phares, Serial No. 71,113, filed March 27, 1936.

In the operation of the burner, gas supplied to it enters through the port 21 and becomes mixed in the throat 20 with the primary air admitted through the port 23. Immediately beyond the throat 20 the mixture of gas and primary air divides, the major portion continuing through the delaying passage 25 and the minor portion being delivered through the port 28 to the explosion tube 29, the latter portion becoming mixed with additional air to create an explosive mixture, as more fully set forth in the co-pending application above referred to. When the explosive mixture in the tube 29 reaches the pilot-burner 30 it is exploded whereby to cause the emergence of a flame from that end of the explosion tube 29 which is adjacent the main burner. By the time the explosion has occurred in the explosion tube 29 the major portion of the mixture of gas and primary air will have reached the annular conduit 10 and will be discharging from the ports 12, so that when the explosion occurs in the explosion tube the gas emerging from the ports 12 will be ignited. If the annular conduit 10 communicated directly with the throat 20 instead of through the delaying passage 25, a considerable quantity of air and gas mixture would accumulate within the housing 16 by the time the explosion in the tube 29 occurred; and if the proportions of the mixture in the housing were within the range necessary to render that mixture explosive in character, an explosion of disagreeable proportions might occur within the housing. Because of the time lag created by the inclusion of the delaying passage 25, however, only a small quantity of gas will have emerged from the ports 12 of the main burner by the time the explosion in the tube 29 occurs, and thus an explosion of major proportions within the housing 16 is prevented.

I find that more efficient burning of the gas within the housing 16 is obtained if the jets emerging from the ports in the bosses 11 are so disposed as to prevent any two of them from coming into direct engagement. To this end, I dispose the ports 12 as indicated diagrammatically in Fig. 5, from which it is apparent that in no case are adjacent bosses 11 provided with aligned ports discharging directly toward each other.

With a burner of the type shown in which the main ports 12 are materially higher than the explosion tube 29 of the pilot-burner arrangement, the end of the tube 29 is preferably located adjacent one of the bosses 11 and that boss is provided with a vertically extending series of aux-

iliary ports 12'. When the explosion in the tube 29 occurs, the flame emerging from the end of the tube will ignite gas emerging from the lowermost auxiliary port 12', and the flame will be carried up the series of auxiliary ports to the main ports 12.

In practice, the effective length of the delaying passage 25 will be related to the length of the explosion tube. This relation may vary considerably depending upon several factors, and is perhaps best determined by experiment. If the delaying passage is too short relative to the length of the explosion tube, the benefit of its presence may be lost, as an explosion in the tube 29 might not occur until after an explosive mixture had formed in the housing 16. On the other hand, if the delaying passage is too long, an explosion may occur in the explosion tube before gas has reached the ports 12'. This latter possibility is not serious; for, if the main burner does not ignite when the explosion occurs in the tube 29, another explosion will occur within a few seconds. In general, I find that the distance gas must travel from the port 28 to the main-burner ports nearest the explosion tube should approximate, or perhaps be somewhat greater than, the length of the explosion tube.

The particular burner structure shown has proven very efficient in use. The annular shape of the conduit 10 permits an adequate supply of secondary air to the center of the area covered by the flames. The ports 12 are directed upwardly and outwardly at an inclination of about 30° to the horizontal, which arrangement tends to reduce the vertical space occupied by the flame. This is of advantage, since if the flame is located too close to a relatively cold vessel on the grid, the gases are chilled before combustion is complete and carbon monoxide escapes unburned. By arranging the ports 12 of adjacent bosses 11 so that the flames from such bosses will be staggered, I prevent a flame from one boss from robbing the adjacent flame from another boss of air and I also prevent the direct impingement of gas streams which would result in a material upward displacement of the flames. All of the features mentioned co-operate to produce a concentration and even distribution of flame, whereby the total horizontal area covered by the flames is reduced to an effective minimum and the greatest absorption of heat by a vessel on the grid is secured.

I claim as my invention:

In a gas-range, an open-topped burner-enclosure, a burner disposed beneath said enclosure and having bosses projecting upwardly thereinto, each of said bosses at its upper end having a series of burner ports, a mixture-supply conduit having a flash-tube port disposed near the bottom of one of said bosses, the boss adjacent said flash-tube port having a row of igniter ports extending from the vicinity of said flash-tube port upwardly toward its burner ports, said mixture-supply conduit continuing past said flash-tube port and communicating with said burner at a remote point, a pilot burner, and a flash tube for conveying mixture from said flash-tube port to said pilot burner.
